(57) **CLAIM**

The ornamental design for end caps for flat panel display mount assembly, as shown and described.

DESCRIPTION

FIG. 1 is a perspective view showing our design for left and right end caps for a flat panel display mount assembly thereof, the broken lines are shown for illustrative purposes and form no part of the claimed design.

FIG. 2 is a perspective front view of the left end cap for flat panel display mount assembly thereof;

FIG. 3 is a right side view thereof;

FIG. 4 is a left side view thereof;

FIG. 5 is a top plan view thereof;

FIG. 6 is a bottom plan view thereof; and

The left end cap is shown separately in FIGS. 2-6 for ease of illustration. The right end cap is a mirror image thereof.

FIG. 7 is a front perspective view of a modified embodiment of the right end cap for flat panel display mount assembly as shown in FIGS. 1-6, the left end cap for flat panel display mount assembly is a mirror image; and,

FIG. 8 is a left side view thereof. The right side view of the left end cap for flat panel display mount assembly is a mirror image thereof.
